UNITED STATES PATENT OFFICE.

ANDREW J. PENNOCK AND THOMAS A. CHANDLER, OF ROCKFORD, ILLINOIS.

IMPROVEMENT IN DEVICES FOR CUTTING PIPE, &c.

Specification forming part of Letters Patent No. 136,004, dated February 18, 1873.

To all whom it may concern:

Be it known that we, ANDREW J. PENNOCK and THOMAS A. CHANDLER, both of Rockford, in the county of Winnebago and State of Illinois, have invented certain new and useful Improvements in Devices for Cutting Pipe, and wrenches for plumbers' and others' use, of which the following is a specification:

Our invention more especially relates to that class of wrenches used by plumbers. Its objects are to adapt the wrench to use in cutting screws, and in cutting pipe, as well as to act upon nuts of differing sizes. The subject matter claimed is hereinafter particularly specified.

The accompanying drawing represents all our improvements as embodied in a single implement; obviously, however, some of them may be used without the others, and in wrenches varying somewhat from the construction herein shown.

Figure 1 represents a plan or front view of one side of our improved ratchet-wrench, showing more particularly the pipe-cutting devices. Fig. 2 represents an edge view of the wrench, its pawls and ratchets being shown in dotted lines. Fig. 3 represents a transverse section on the line $x-x$ of Fig. 1, through a portion of the body of the wrench, looking toward the cutter. Figs. 4 and 5 represent longitudinal sections through the handle-heads, showing their ratchets. Fig. 6 represents a section through one of the ratchet-heads. Fig. 7 shows a face view of, and a section through, the screw-tap or die-plate. Fig. 8 represents the body with the tap inserted. Figs. 9 and 10 show the handle-heads detached. Fig. 11 represents one of the ratchet-heads with its adjustable nut-holders.

We construct our improved wrench, by preference, in the following manner: Its body, A, is of cylindrical form with a longitudinal slot, a, in it extending to its central cavity a^1 . (See Figs. 1, 3, and 8.) A flanged head, B, is formed on one end of this body. A cutter-arm, C, carrying a cutter, c, vibrates on a pivot, c^1 , in a recess in the face of this head, moving parallel therewith and transversely to the axis of the cavity a^1 . A spring, c^2 , bears on the back end of the cutter-arm to retract it when free. A suitable plate covers the spring.

The cutter is fed forward by means of a feed-screw, C'.

An implement constructed as above described can be slipped laterally over any portion of a pipe of suitable diameter, and the pipe can be severed by turning the implement, the cutter being fed forward by turning the feed-screw by hand as the cut deepens. We prefer, however, to render the feed automatic, and thus increase the utility of the implement.

To do this we mount a handle, D, (with a head slotted as shown in the drawing,) upon the body A, so as to fit snugly but turn freely thereon. A segment-rack, d, on this handle engages at each revolution with a gear, c^3 , upon the feed-screw, thus causing it to turn intermittently, to feed the cutter automatically as the cut deepens. To adapt the wrench to screw-cutting, we insert a tap or die plate, E, in a transverse groove, e, in the body of the wrench. This tap is applied to the point where the screw is to be cut, and worked as other dies are. To adapt the wrench to nuts of varying sizes we form transverse dovetail grooves f in the body or head, in which clamps F slide, being held in any desired position by set-screws f'. As in many positions the handle of the wrench cannot be turned entirely around, a ratchet arrangement becomes indispensable to effective work. We therefore form a ratchet-ring, b, on the inner face of the head B, into which a spring-pawl, d', working in a recess in the handle takes, as shown in dotted lines in Fig. 2. This device, however, while effective, will only produce an intermittent rotation, whereas, for rapid work, a continuous movement is desirable. We therefore apply another head, B', to the body A, (see Figs. 6 and 11,) and construct a ratchet, b¹, on its inner face. A second handle, D', is applied to the body, but in reverse position; its pawl a² working into its ratchet b², as above described.

Both handles, it will be observed, move round the head in the same direction; either a right or left hand nut can be unscrewed by applying the corresponding face of the wrench, as one set of the clamps turns to the right, and the other to the left. The handle-heads being slotted transversely as well as the body of the wrench, the implement can be applied later-

ally to any portion of a pipe with facility; the screw-tap can also easily be removed and inserted, or replaced by one of different size, and yet is firmly held while in position. Both handles can be turned around the body together or independently of each other. We thus by our invention combine many valuable features in a single implement.

We do not broadly claim a two-handled ratchet-wrench, as such implements heretofore have been patented; but their construction and operation differ essentially from ours.

We claim as our invention—

1. A ratchet-wrench constructed substantially as set forth, with a rotating tubular body slotted longitudinally to permit of the insertion of a pipe sidewise.

2. The combination of a tubular body, an adjustable cutter, and a feed-screw or its equivalent acting upon the cutter, these members being constructed and operating in combination, substantially as set forth, to advance the cutter as the cut deepens.

3. The combination in a ratchet-wrench of a rotating body, carrying an adjustable cutter and a feed-screw, with a rotating handle, and a rack upon it, these parts being constructed

and operating substantially as set forth, automatically to feed the cutter.

4. The combination in a ratchet-wrench of a longitudinally-slotted rotating tubular body with a die-plate movable transversely in a groove in the walls of the slot, substantially as set forth, securely to hold the die-plate, and yet admitting of its ready removal or replacement.

5. The combination in a ratchet-wrench of a rotating tubular head with clamp-plate adjustable transversely therein, substantially as set forth, to adapt the implement to nuts of varying sizes.

6. The combination in a ratchet-wrench of a rotating longitudinally-slotted tubular body with handles having longitudinally-slotted heads, these members being constructed and operating substantially as set forth, so that a pipe or similar article may be inserted sidewise and then encircled completely by the implement.
